SHOULDER FIREARM

Francis P. Sloan, Wilton, Conn.

Application January 27, 1947, Serial No. 724,562

6 Claims. (Cl. 88—2.4)

1

This invention is a novel shoulder firearm, being a gun which is adapted to be manually carried and operated, and which carries both a gun sighting means for use in adjusting gun elevation and a range finding means; these three general elements, the gun, the sights with the setting device for the rear sight, and the settable range finding means being, pursuant to the present invention, combined in mutual interrelation, in a manner to be described, to give advantageous cooperation between said elements in practical use.

The improvement is widely useful, affording an improved construction and operation for rifles and other shoulder firearms of various types such as the U. S. Army Springfield rifle, the Enfield rifle, the Garand rifle etc.; a typical instance upon which the invention may be embodied to advantage being the Springfield rifle, bolt-operated, semiautomatic in action and handling 5-shot cartridge clips. The invention is particularly useful for war purposes and big game hunting, with various shooting ranges up to 600 yards more or less.

In the prior art of shoulder firearms, of course, gunsights have long been standard equipment wherein, knowing the range, the sighting means may be readily set or adjusted, frequently by raising or lowering the shiftable rear sight, so as to give to the gun the proper elevation to cause the bullet to be delivered with a trajectory to strike the target. In the art of range finding there have long been well known instruments of various types and for various uses, including the aiding of shooting; and these are customarily operated, especially for war use, by an officer or associate of the gunner, permitting the latter thus to be apprised of the range and appropriately to set his sights accordingly. One important class of range finders is the monocular, which is free of the complications and inconveniences of binocular instruments. No instance is known by applicant of a gun carrying in cooperatively combined relation a rear sight setting means and a monocular range finding means.

Broadly the present invention presents the association of the three general elements, the gun or shooting firearm, and mounted thereon the sighting means or gunsight for aiming the gun for a given target, and also mounted thereon the means for determining the range of the target to assist the purpose of properly adjusting the rear sight to provide the proper elevation of the gun to cause the trajectory of the fired bullet to meet the distant target; matters of allowance for windage and other factors than elevation being

2

independent factors and unnecessary to elucidate for the purposes of the present invention.

At the outset it may be conceded as having been suggested, before the present invention, to combine in a broad sense a gunsighting means and some form of range finding means both carried upon a shoulder firearm; but so far as is known these three general elements have not heretofore been operatively combined, at least in monocular form or with a base type of finder, in a manner to afford a cooperative combination of the elements; the gunsight of the most pertinent known prior suggestion serving its function for setting the elevation of the gun, but the range finding means having no more relation to the other elements than its being carried for convenience upon the gun as a handy support, and having no more combination relation or cooperation with the gunsight means than has the rubber eraser at one end of an ordinary pencil with the lead serving the writing function at the other end; on the gun as on the pencil these elements being in aggregation rather than combination, and having distinct disadvantages, such as the non-functional and objectionable adding to the weight of the complete gun with gunsight the substantial further weight of a complete range-finding means, which might with greater advantage be operated independently, either by the gunner or an associate, to determine the range of the target in preparation for the corrective sighting and firing of the gun.

It is an object of the present invention to provide on a firearm a novel and useful general combination therewith of gunsight means and range finding means, involving coating features of form, arrangement and structure. A further object is to afford a special and complete mode of cooperative action of said three elements, by means of novel and specific interrelated features of form, arrangement and structure, including mutual interconnections or a common control serving to provide the aforesaid cooperation in a manner to be hereinafter more specifically described and explained. A particular object is to provide, for a shoulder firearm, and in cooperation with the settable shooting sights thereof, a specific type and form of range-finding means, and with such interconnection between the two that when the range-finding operation has been performed and the range thus determined the shooting sights will have become automatically set to produce a gun elevation corresponding to the target range so determined.

To the attainment of the recited objects and

advantages the present invention consists in the novel shoulder firearm, herein illustratively disclosed and described, and more especially the combination with the firearm or gun itself of its front and rear sights and their setting device and a range-finding means and its setting contrivance, all arranged and operable to afford the actions and results hereinafter more particularly set forth. More particularly the invention consists of certain intercombinations of cooperative elements which may be viewed in different aspects. In one aspect the firearm hereof has for its front and rear shooting sights a shiftable rear sight setting device to lift or lower the rear sight and so coordinate the elevation of the gun with the range of the target; the gun carrying also mounted thereon a monocular type, as the base type, of range-finder having a shiftable setting member or contrivance operable to determine under visual observation the range of the target; and a common adjuster or controller, as an adjusting cam means, which mechanically interconnects, and is operable under such visual observation to shift and set, in the same action, both said setting device and said setting contrivance in such coordination that when the adjusting means is operated to set the range-finder to the range of the target this action automatically sets the rear sights for a gun elevation corresponding with such range.

In another aspect the invention consists of the gun with shooting sights as before but characterized in that, cooperative therewith, the gun carries also an optical range finder of the base type wherein plural images of the target are visually observable and may be brought into register or coincidence by the setting of the range finder; the range finder having rear and front optical elements or reflectors spaced apart upon its base line, which base is of substantial fixed length and is located adjacently alongside, preferably lengthwise above, the gun barrel, with its observation point near the rear sight, the rear reflector being angularly settable for combining the two light beams thereby to bring into register the two images of the target; the range finder having a shiftable setting contrivance operable by observation thus to set such rear reflector and thereby bring the plural images into mutual register or coincidence, and thus to determine the range of the target; so that the gun may be held comfortably by the shooter in its range-observing position transverse to the line of fire or direction of shooting, and with the center of gravity of the gun approximately near the gunner's head, providing an easy balance during the range-finding operation, and so that the gun may thereupon, when the range has been determined, be readily shifted from transverse to longitudinal position for shooting action after the setting of the gun sight to the target range.

In a further and preferred aspect the invention consists in the complete combination of the elements thus far recited, with the same gun sights and the setting device or mechanical connections therefor, also the base-type range-finder, mounted with its base line adjacently lengthwise the gun barrel and of substantial length approximately coextensive with that of the barrel, having also a shiftable setting contrivance or connections operative to determine under observation the range of the target; combined with the common adjusting means or controller, shown as a cam, which is operably con-

nected both to the setting device and to the setting contrivance to shift them simultaneously in such coordination that the elevation of the gun in any and every setting of the sights corresponds automatically with the range determined by the setting of the range finder.

In the accompanying drawings showing an illustrative embodiment of the invention, Fig. 1 is a range finding diagram in top plan view, with great exaggeration of the angular divergence of the paths of the two light beams received from the target, the firearm being shown as held in finding position.

Fig. 2, in three parts 2^a, 2^b and 2^c, presents image alignment or registering diagrams, with the gun held horizontal, erect images being shown in process of alignment upon a given reference line or hair line. Fig. 3 is a similar diagram but with the gun vertical. Fig. 4 is a similar diagram showing alignment when the gun is held in some other or slanted position. Fig. 5 is a diagram showing a different kind of alignment or coincidence, an erect image in register with an inverted one. Fig. 6, in two parts 6^a and 6^b, presents diagrams showing two erect images being brought into complete coincidence as when a transparent mirror is used to afford simultaneous viewing of superimposed images of an object or target. These various operations are 30 performable upon the gun of the present invention, as will further appear.

Figs. 7^a and 7^b constitute similar perspective views of the more important rear and front parts of a gun embodying the present invention, with the gun rear end and much of its middle portion omitted; Fig. 7^a showing the breech portion of the gun from the line 7^a of Fig. 1 rearward, while Fig. 7^b shows the front portion of the gun from the line 7^b of Fig. 1 forward; the base range finder requiring the use of well spaced-apart optical elements or beam-bending reflectors shown as the prisms A and B near the rear and front ends respectively of the barrel, at the front end there being a beam receiving or collecting element and at the rear end a beam combining and viewing unit, at or near the breech.

Fig. 8 is a top plan view of the breech of the gun together with the rear sight and the rear or beam-combining unit of the range finder, together with the various devices, members and mechanisms associated therewith.

Fig. 9 is a righthand elevation of the rear unit mechanism shown in Figs. 7^a and 8; while Fig. 10 is a front elevation, Fig. 11 a lefthand elevation, and Fig. 12 is a rear elevation of the same.

Fig. 13 is a front elevation of the muzzle end of the gun showing the front sight and the beam collecting and transmitting means, all mounted upon the gun barrel. Fig. 14 is a lefthand elevation of the parts shown in Fig. 13; while Fig. 15 is a righthand elevation, Fig. 16 a rear elevation, and Fig. 17 a top plan view thereof.

Fig. 18 is a top plan view of a certain saddle member or block which constitutes a base for the rear unit of the invention and which is fitted upon and attached fixedly to a cross arch or bridge as conventionally exists at the breech of the firearm. Fig. 19 is a righthand elevation of the right end plate of the saddle of Fig. 18.

Fig. 20 is a top plan view of a swingable carriage or turret which is supported by the saddle block and which in turn gives support to the beam-combining or rear unit of the range finder; and Fig. 21 is a front elevation of said carriage while Fig. 22 is a righthand elevation thereof.

Fig. 23 is a perspective view of a frame guide or slideway upon which is slidably supported a certain rear sight bridge, for rising and lowering adjustment of the latter.

Fig. 24 is a top plan view of the rear sight bridge, while Fig. 25 is a rear elevation thereof; Fig. 26 being a rear elevation of the peep hole plate constituting the rear sight, and Fig. 27 a central vertical section through the same looking from the righthand side; Fig. 28 being a vertical section of the sight bridge of Figs. 24 and 25, taken centrally through the same and looking from the right side; Fig. 29 being a detached top plan view of the sliding plate shown in Fig. 28 which connects the sight bridge to the guide or post member shown in Fig. 23, and Fig. 30 a rear elevation of said sliding plate.

Fig. 31 is a top plan view of the housing, shown also in Fig. 7^a and Figs. 8 to 12 for the beam-combining rear unit of the range finding means; while Fig. 32 is a righthand elevation, Fig. 33 a rear elevation, Fig. 34 a front elevation, and Fig. 35 a left elevation, of the same.

Fig. 36 is a top plan view of the common operating means, controller or adjusting cam preferably employed for effecting both the sight-setting and the range-finding adjustments of the invention; while Fig. 37 is a rear elevation of the same; Fig. 38 being a vertical section taken on the line 38—38 of Fig. 37, and Fig. 39 a vertical section taken on the line 39—39 of Fig. 37.

Fig. 40 is a top plan view showing the beam-combining unit of the range finder, and optionally associated therewith a telescope adapted to afford magnification of observed images during adjusting or range finding operations; Fig. 41 being a front elevation of such telescope, and Fig. 42 a left elevation of the same.

Fig. 43 shows in diagram one form of beam reflector or prism adapted to receive a normal light beam and reflect it, as internally, for transmission along a light path at substantially right angles to the entering beam.

The drawings show, as one illustration of the invention, a gun 53 of a conventional kind, the term gun being intended to include any shoulder firearm, whether of rifle or other class. Some of the general gun parts are shown and designated by reference number, while other parts are either shown but not so marked or are omitted as unnecessary for a disclosure of the present invention. The illustrated firearm 53 has the gun barrel 117, of suitable bore, and overlapping therewith the usual gun stock 117X. Associated with these are comprised the conventional cartridge handling and firing and other operating parts. The firing chamber constitutes a rear enlargement of the bore, and within it operate the firing bolt and pin, retractible to make way for the insertion and extraction of cartridges; there being shown a cartridge-clip slot 54 within the chamber. At the underside of the stock appears the customary trigger 54X, for causing the firing action. Arching across, at the gun breech, below the position of the rear sight 63 to be described is shown the preexisting cross bridge 52, a permanent fixed part of the gun, which is utilized as a support for the mounting of the rear sight and its adjusting mechanism, there being shown a saddle block or base member 51 attached fixedly atop the cross bridge 52, this herein giving mechanical support to the rear sight and to the rear elements of the range-finder means.

As already indicated, the invention relates both 75

to the settable sight means upon a firearm and to the cooperating base-type range finder thereon. The invention is distinguished from the mere addition of a sighting telescope to a gun, even though the focusing thereof may indicate the range; such a plan adding greatly to the burden of weight and presenting other drawbacks without being of practical value in the setting of the sights to the range. The invention is distinguished also from any plan for the mere applying upon a gun of a base-type range finder of which the base line is not disposed substantially lengthwise the gun length, or which finder is operable while the gun is held longitudinal to the line of fire; for in such cases either the range base is too short for accuracy or the structure projects prohibitively crosswise.

The present invention uses the true baseline or triangulation principle (see Fig. 1) and does so in a manner to afford an ample base, namely, by placing it longitudinally to, and thereby using substantially the full length, of the gun barrel, and so giving greatly multiplied accuracy. Two target-viewing optical elements are provided for range finding, one element or reflector B near the front sight at the muzzle end, and the other element A adjacent to the rear sight at the breech end of the barrel. These reflectors A and B cooperate to render observable the twice-bent one of the two images required to be set to coincidence in this type of finder. For range-finding, the firearm hereof is first held across the line of fire, with the shooter's eye E close to the optical observing element at the breech, as the usual gun sling readily permits. The left hand grips the fore-stock in the usual manner, the butt rests on the right arm near the elbow and the gun remains steady while the right hand reaches around to the setting thumbscrew or member 33 to be described and thereby adjusts the optical elements until the plural images of the target are brought into register, thus finding the range.

Using the complete invention, with the manual adjusting of the range-finding elements under observation, the action simultaneously shifts the setting device of the rear sight 63, and thus sets the sight to deliver the correct gun elevation for the found range. Thereupon the firearm is easily swung 90° into firing position. The left hand continues its grip on the fore-stock and the right hand quickly and easily slips down into position for the trigger squeeze. The complete finding and shooting operation are performed naturally and with but little effort and the eye need not be removed from the target.

The optical elements may be those of any true base type or coincidence range-finder or telemeter having the two spaced-apart optical elements, namely, the beam-collecting element with reflector B and the beam-combining element A, thus producing for the gunner's observation the twice-reflected target image and a second or direct image, in one ocular or field of view, the setting means and movements being such that one image may be brought into alignment or coincidence with the other, with a different setting for each range. The beam of one of the images may be twice bent, passing the length of the barrel between reflections, and the second reflector of this beam, near the rear sight, may be the one by which the setting is effected, for example by a minute angular swing or rotation upon a pivot or axle, continued manually until the first and second images are seen to be in perfect register.

While a reading of range by scale and index could be made, and then translated manually to sight setting and elevation; with this invention, as illustrated, the two operations may be and are coupled, by a duplex common adjusting means, with for example a single hand piece as the thumb-nut 83. The rear sight may for this purpose be not only adjustable as to elevation but adapted by its coupling or interconnection with the moving elements of the range-finder to set the sight automatically for a gun elevation in accordance with the range. The front sight 115 may be stationary and of any standard type.

As a matter of definition the muzzle end is herein treated as the front end of the gun, and the butt or stock end the rear; the sight nearest the shooter is the rear sight; and when the gun is in shooting position the view seen from the righthand side of the shooter is considered the right elevation view of the gun, and the same with the various parts thereof, and vice versa.

The embodiment of the invention which is illustrated in the drawings shows it adapted to the physical structure and dimensions of the U. S. Army Springfield rifle, caliber 30, Model 1903; but the invention is not to be limited to this firearm or to the details thereof.

The invention serves the important purposes, inter alia, of (1) improving the accuracy of firearm aiming by providing a practical finding instrument by which the gunner can measure reliably the distance over which the bullet is to travel in its curved trajectory; (2) providing for such purpose a portable coincidence range-finder affording a long baseline without requiring the soldier or hunter to carry both the gun and an additional instrument; (3) providing a small, compact and lightweight range-finder attachable to any military or hunting shoulder firearm without requiring major alterations of the firearm or interfering with its primary utility, and with its front elements attached to the gun preferably independently of the mounting of its rear elements; and (4) providing such a range-finder and a settable rear sight combined for automatic coaction in the setting of the elevation by the action of finding the range.

Referring to the particular embodiment of the invention shown in the drawings, the general or range finding diagram of Fig. 1 shows in plan view a suitable method of holding the firearm for this operation, together with an optical diagram of the triangulation of the finder with the target T. The target distance or range is represented by the length of the line TA. The baseline AB is the line between the rear or beam-combining elements or unit A and the remote or front elements or beam-collecting and bending unit B. The line TA is the direct line of sight. The line TBA is the indirect or deflected line of sight, bent at A to reach the observation point E.

The values of the base-line AB and the angle TBA are both known and fixed. Thus AB is the lineal length longitudinally along the gun barrel between the front finder elements, particularly the collecting and first bending element, reflector or prism, designated B, and the rear elements, particularly the combining and second bending element, reflector or mirror, designated A. Thus also, as to the angle TBA, this is the predetermined invariable angle subtended between the longitudinal light path or axis from B to A and that beam or light axis which when bent and reflected by the pre-fixed reflector or prism B will

travel along such axis or path BA as it must do to reach the reflector A. The fixed angle TBA could advantageously be 90°, but a prism B giving a slightly smaller known deviation angle, under 90°, may be used. Thus the front reflector could well be such, and so fixed in position, that when the target T is at some mean range, as 400 yards, the direct image viewing line or axis AT will stand approximately at 90° to the base line AB, as the Fig. 1 diagram indicates; in which case when the range is lengthened the rear reflector must be rotated slightly clockwise to register the two images, while the gun is swung oppositely, displacing its muzzle and slightly from the target, these actions being reversed for a shortened range.

The angle TBA being fixed, the angle TAB is of course a variable one and is, for each operation, set or measured by rotating the rear deflector A about its vertical axis or pivot bearing, as will be described. The distance TA is the range, and its value is determinable from the known angles and the length of the included baseline; and the value is usually indicated by a scale with an index or pointer and graduated to show the range, the adjuster or thumbscrew 83 being the means of shifting angularly the reflector.

Figs. 2 to 6 are diagrams of various fields of view obtainable in different ways through the optical elements of this invention, with the (triangular) images of the target separated or in register, as will be explained in detail hereinbelow.

The perspective view of Figs. 7^a and 7^b shows the breech portion and muzzle end of the army rifle with its front and rear sights and adjacent parts of the range-finder mounted near the ends of the barrel 117. The several views of Figs. 8 to 12 show more completely the rear sight and rear finder elements and their mounting and operating means, to be more fully referred to.

The figure group 13 to 17 shows front-end sighting and finding means in greater detail than in Figs. 1 and 7^b. The figure groups 18 to 19, and 20 to 22, and 23, and 24 to 30, and 31 to 35, and 36 to 39 show rear-end parts with further details of the sighting and finding means.

Figs. 40-42 show a portion of the rear-end mechanism, with a telescopic instrument attached at the observation ocular of the range finder, which may be desirable with excessive ranges or small targets.

For the purposes of further description, the relevant additions to the gun may be divided, as they are in Figs. 7^a and 7^b, into two groups of parts, namely, the rear parts including the rear sight and adjacent finding elements with their mounting and operating means, shown in Fig. 7^a; and the front parts including the front sight and adjacent finding elements, shown in Fig. 7^b. These two groups, more particularly the near and remote optical elements or reflectors A and B, are separated, in an optical sense, by the length of the baseline of the finder, that is, the base of the triangle by which the range is to be measured.

Referring first to the rear group assembly this comprises an attached saddle-shaped base or supporting block 51, Figs. 8, 18 etc., hereafter called the saddle, built up of two seating bars connected by end pieces, best seen in Fig. 18, the whole mounted fixedly upon the permanent bridge 52, and somewhat to the rear of the cartridge-clip slots 54, by attaching screws or other means, not

shown; the saddle supporting directly or indirectly a number of other parts, including a forward extension or shelf 51Y for the rear optical elements.

This saddle or attached base piece 51 supports directly a two-legged open frame or upright guide piece 55, Figs. 8, 23 etc., having dovetail tracks or channels 56 adapted to guide a dovetail slide or elevating plate 57, Figs. 24 to 30, and having a top bar or stop 58 to limit the upward travel of the slide 57 by the contact with the top bar of a stop pin 59 projecting from the slide. The upstanding guideway 55 has below its legs two peg extensions 55X fitting into a pair of holes 51X in the front bar of the saddle, permitting the guideway to be secured as a unitary part of the saddle.

Loosely attached to the elevator slide 57 by a lower pin or pivot 60, allowing some swinging motion or play to prevent binding during lifting, is a horizontal cross-part herein termed the sight bridge, 61, which carries the apertured rear sight 63 shown as a plate. The liftable bridge 61 is centrally open to surround the upright guide or frame 55. Said sight bridge at will, to maintain a given elevation, may be clamped adjustably to the guide 55, at any selected height, as by a clamping screw 62, whose operating head or thumbpiece is seen at its righthand end, Figs. 7a, 8, 24 etc.

The sight bridge 61, which carries the rear sight 63, may be operatively raised or lowered by the crosswise shifting or sliding of an important mechanical element, a common adjuster, controller or cam means 78, Figs. 7a, 36 to 39 etc., to be further described; and the sight bridge and sight may also be lifted independently by hand temporarily to a high inoperative position (the adjusting controller 78 acting by an open cam) and may be fixed there by the clamp screw 62, before the range finding operations. Thereafter the sight bridge may be unclamped by screw 62 and lowered into operative contact with the upstanding cam part or elevating face 77 of the common adjuster 78, thus to lower again the rear sight 63; and then if desired, range finding having been effected, the sight bridge may be clamped in its lowered or shooting position by the same screw 62. On the other hand the rear sight carrying bridge 61, or rather its follower contact 76, may be maintained as by spring pressure in constant contact upon the elevating cam part 77, shown as an open cam, since wear is negligible, and indeed a closed cam could be used, with a follower acting to raise and lower the bridge and sight, thus giving positive positioning of the sight with an elevation corresponding always with the range which the range-finder setting may represent.

The rear sight 63 may take different forms but is shown as a small plate 63 formed with a sighting notch or preferably a peep hole 65 as seen in Figs. 7a, 10, 12, 26 and 27. It is mounted for horizontal slide adjustment upon the sight bridge 61 and rises and lowers with it, for elevation. The slidable sight has a threaded rear lug or nut 64 which extends through a horizontal slot into a transverse way 61X formed in the sight bridge rear wall, thereby to permit left and rightward adjusting shift of the sight.

By the structure thus described the sight bridge 61 is adapted for windage adjustment, carrying laterally slidably the rear sight or peep-hole plate 63, whose threaded lug or nut 64 is shiftable in the bridge slot and slideway 61X. Engaging the

threads of this lug or nut is a windage setter or screw 66 borne by the bridge and having a thumbpiece or knurled head 67 at its left end, and there being a compression spring 68, Figs. 5 7a and 12, at the right, opposing the rightward movement of the nut 64, and thus preventing loose play. This arrangement provides the conventional type of windage allowance by lateral adjustment of the rear sight.

10 To ensure sight through the peep-hole in all adjustments an elongated hole or through aperture 69 is provided in the rear side wall of the bridge 61, and a similar but vertically wider aperture 70 is formed in the slide 57, see Figs. 25, 28 and 30, thus to permit an unobstructed view through both bridge and slide. The front wall of the bridge is also cut away at 71, Fig. 28, in the line of sight, for the same purpose. The nearby opening 72 in said front wall is provided for access, during assembly, to the stop-pin 59 of the upright slide plate 57.

The illustrated sight bridge 61 carries at its rear side above the rear sight a graduated scale 73 attached adjustably in place by a clamping

25 screw 74, which is to be tightened fixedly after the initial or test "sighting in" of the rifle, Figs. 7a, 8-12, 24, 25; thus standardizing the position of the scale relatively to the sight. The peep-hole plate or sight 63 carries a pointer or index 30 mark 75, Figs. 7a, 12 and 26, which registers with, as it shifts along, the graduations on scale 73, thus to assist the operation and indicate the adjustment for transverse winds.

35 To take part in its vertical adjustment the sight bridge 61 has a downward contact projection or follower 76, Figs. 7a, 25 and 28, adapted to bear down and rest upon the top cam part or face 77 of the adjuster or cam means 78, so that the cam as it slides leftward or rightward can raise or lower the bridge and rear sight, according to the contour of the cam face. This follower 40 76 and parts between it and the sight may be considered as constituting a device for setting the sight, operated by the cam part 77 of the adjuster 78.

45 This common controller or duplex adjusting cam is mounted to slide leftward and rightward upon the upper face of the saddle block 51, the cam body 78 preferably carrying not only the 50 sight setting cam part but also the finder setting cam part. The duplex cam comprises the upwardly extending cam part 77 with contoured face for sight elevation and the rearwardly extending part 86 with contoured face for range-finder adjustment, see especially Figs. 7a and 36-39. For its adjusting movements the cam body has a downwardly protruding threaded extension or nut 79 formed with dovetail sides 80 prolonged beyond the nut and adapted to engage

60 and slide between the matching or opposite sides 81 of the guiding slot or transverse recess formed between the front and rear bars of the saddle 51, Figs. 8, 18. The threaded nut 79 of the adjuster cam is engaged by the threads of an adjuster 65 screw 82 which at its right end carries a knurled thumbpiece or screwhead 83, Figs. 7a, 8-12, 36-37. The screw shank is formed with a circumferential groove 84 which is engaged by a fixed pin 85 upstanding from the right end of the saddle, Figs. 8, 18 and 19, these parts preventing the longitudinal movement of the screw 82 and thus compelling the rotation of the screw by the adjusting knob 83 to slide the control cam 78 transversely upon the upper face of the saddle, and, 70 by the contact of top cam part 77 with the pro-

jection 76 of the sight bridge 61, to raise or lower the bridge and the peep-hole rear sight 63 which it carries.

By the construction thus described the rear sight setting device or mechanism, consisting of the movable sight bridge 61 and the depending contact or follower 76 thereof, is operated by the cam part 77 of the common cam means 78. Likewise, in regard to the finding of range, as will be further described, the rear optical elements, especially the rotary reflector, may be said to be provided with a setting contrivance or mechanism, in this case comprising a movable arm or swinging lever 88 and the terminal contact or follower 87 thereof, actuated by the cam part 86 of the duplex cam means 78. The common adjusting means or duplex controller may thus be considered as comprising the cam means generally or its body 78, the sliding operation of which by the controller screw 82, 83, serves both to actuate the cam part 86, operating through members 87 and 88 and others for finding the range, and to actuate the cam part 77 operating through the elements 76 and 61 to set correspondingly the vertical position of the rear sight and thereby the elevation of the gun, for any given distance of target. The companion cam parts, always in definite relationship, provide automatic operation and timing of range finding and gun elevation; whichever one being under observation during setting, the other receiving the complementary setting.

Thus, the duplex adjusting or double wedge cam 78 has its rear cam part or extension 86 formed with a cam face taking part in range-finding; its contour being accurately formed to cause the rotational setting of the rear optical element A in coordination with the setting of the rear sight 63 determined by the cam part 77. The second or horizontal cam part 86 has its face in continuous contact with the follower contact 87 at the left end of the long horizontal arm of a lever 88 pivoted at 89 atop the saddle, the other or short arm of the lever making thrusting contact with the free right end 90 of the long arm of a second transverse lever 91 pivoted on the saddle at 92. The contact point 87 is pressed against the open cam 86 by a spring 93. The second or short end of the second lever 91, having but a minute swing, engages the rounded end of a contact screw 94, Figs. 7a, 20 and 21, which is threaded into and carried by the rear goose-neck or extension arm 95X of a swingable carriage 95 having an interior round hole by which it is pivoted near its front end upon the front extension shelf 51Y of the saddle 51, Fig. 18. The pivoted carriage 95 carries the base 96, Figs. 7-11, of the beam-combining or rear optical unit A, as will be described, whereby the shifting of controller cam 78 by the thumb-nut 83 changes the range-finder setting. The screw 94 may conveniently be used initially to standardize the adjustment of, or to "sight in," the range-finder.

The carriage 95, rotatable on upright pivot 97 through a small angle, is in effect a turret, supporting and conveying angular adjustment to the housing 106 and to the near or rear reflector A, which may have its reflecting surface upright and approximately axial with the turret, so that during image registering operations the base line length between the remote and near reflectors is not changed.

The thrust of the short arm of lever 91, acting upon the carriage arm contact 94, swings the arm and the carriage 95 to give the latter and the

optical element A the minute angular adjusting motion necessary for range finding purposes. With the cam face 86 suitably designed and laid out, the scale 112 may be ruled with equal scale increments for equal increases of range, thereby affording convenience in range finding and simplifying the laying out of the companion cam 77 which elevates the rear sight; which sight may have a separate indicating scale, although the interconnection of the two cams and the parts beyond makes this unnecessary. By the described elements 87 to 94 is provided a mechanical train, or operating contrivance, extending from the duplex adjusting cam 78, 86, by which the carriage 95 and the rear optical member or reflector A thereon are given their minute angular setting adjustments under the range-finding principles already explained; while the train 76, 81 and 64 constitutes the device or connections from cam 78, 77 to the rear sight 63.

The swinging optical carriage 95, by reason of its vertical pivot hole, can rotate around the fixed pivot 97 (Fig. 18) on the saddle extension 51Y, which pivot is slotted at 98 to receive and hold a flat or strip spring 99 which may be initially curved or straight and which contacts the carriage 95 at 100, Fig. 20, and which, being under constant bending strain for counterclockwise carriage swing, tends to press the carriage contact screw 94 against the short arm of lever 91, thus keeping the lever free of loose play, and ensuring continuity of train. The pivoted carriage 95 is held down in close contact upon the upper face of the saddle 51 by any convenient overhanging part such as the head of a post or screw 101 (Fig. 20) passing through a slot 102 in the carriage, and screw-threaded into the saddle extension 51Y; the slot being concentric to the pivot stud 97 and the post head having a working fit to permit carriage swing.

Atop the swingable carriage 95 is a dovetail slideway 103, the opposite sides of which accommodate between them the fore-and-aft slidable housing base 96 which in turn supports at its front and rear ends two housing collars or bearing rings 104 and 105 which accommodate between them the optical housing 106 for the ocular and the beam-combining unit A of the range-finder. These parts 103 to 106 all partake of the range-finding swinging movements or angular shifting of their supporting carriage 95 produced by cam part 86 through levers 88 and 91.

The rear unit housing is cylindrical at least at its ends 104, 105, and is capable of a slight adjusting rotation around a horizontal axis substantially parallel to the base line of the range-finder, and axial to its bearing rings 104, 105. The housing however is held against longitudinal movement by the flanged shape of the front ring or collar 104 and by a pin 107 extending through circumferential short slots in the collar 105; the ends of which pin serve as convenient projections or knobs for the rotary adjusting manipulation of the housing when in use. The described rotation of the housing about its own horizontal axis functions for adjustment to bring the target into view before its range finding rotation about the vertical axis of carriage swing.

The optical base 96 is assumed to have been fixed to the pivoted carriage 95 by a pin or other means, not shown, after the base has once been set accurately to place the rear optical element A at the predetermined base line distance from the front beam-collecting unit B.

The housing 106 is shown with several optical

openings or windows. See Figs. 7 to 11 and 31 to 35. Openings 108 and 109 are righthand and lefthand opposite side windows forming the opposite ends of a lower light beam passage or shaft for the substantially direct viewing of the target, the direct beam TA Fig. 1 entering the opening 108 and leaving through the opening 109. Another opening 110X, Fig. 10, is an end window for the receiving face 110 of the optical reflector A which is shown as an isosceles right angle deflecting prism receiving longitudinal beams reflected from the front beam collecting unit B. The fourth housing opening 111X is a left window for the exit face 111 of the same prism A, through which face and window the beam BA after bending passes transversely out of the housing to the observer's eye. The lower and upper exit openings 109 and 111X preferably are physically a single window opening, the optical dividing line 134 between them, Figs. 11 and 35, being at the bottom surface of the prism, this being referred to as the "halving line," standing between the two observed images. See also Figs. 2-5. These openings in combination with the reflecting prism A may constitute the ocular of the range-finder, presenting to the observer, adjacently one above the other or side by side, the two images, direct and twice-reflected, to be adjusted into coincidence or register by the range-finding operation.

The ocular, by its housing 104-106, thus provides apertures for the separate admission of the two beams BA and TA (or TE) and for the joint or adjoining egress thereof for comparative observation, e. g. with one image at each side of the halving or coincidence line 134; their registering consisting in adjusting the first image along said line until it aligns with the second image upon the reference line 125.

For convenience the saddle 51 is shown as carrying a range scale 112 marked off in any appropriate unit of target distance between the upper and lower limits within which it is desired to use the range-finder and/or the rear sight. See Figs. 7, 8, 10, 18 and 36. The drawing shows ranges from 100 to 600 yards as appropriate for the army rifle as used without a telescope. A pointer or index 113 on the slidable controller or double wedge cam 78 registers with the graduations of scale 112, and thus indicates at all times the range for which the rear shooting sight is adjusted. By screws 114 (Fig. 18) the scale is mounted on the saddle, with transverse slots to permit initial adjustment of the scale for standardizing its position when the range-finder is being adjusted or "sighted in."

The rear optical element A is essentially a reflector to change the beam TBA from longitudinal to transverse direction relatively to the base BA and the gun barrel, thus bending and directing the image to the eye in position juxtaposed to the direct image seen along the line TA for observation and comparison during adjustment. While a mirror could be used to bend the beam or ray, a prism is shown; and in Fig. 43 is presented an available form of prism A, being a conventional right angle triangular prism, preferably isosceles.

The front sight 115, with its hood 116, and the adjacent optical elements, are shown in Figs. 7^b and 13 to 17. The front sight may be mounted in any usual way at the muzzle end of the barrel 117, in front of and higher than the optical elements. The latter comprise a beam-collecting unit containing the reflector B enclosed in a housing 118 whose bottom wall or base 119

has depending dovetail projections shaped and tapered to engage with wedging fit the upstanding ears of a strap 120 encircling and clamped to the barrel. The housing 118 may be locked in place by a pin 121 and the strap may be fixed against rotation by a lug 122.

The housing 118 for the front optical means is formed with two optical openings or windows 123X and 124X respectively facing rightward from and rearward along the base line and barrel. Within is the reflector B, shown as an isosceles right angle prism as in Fig. 43. The first prism face 123 receives the light-beam TB from the target through the window 123X while the second face 124 transmits through the window 124X the rearwardly deflected beam to the reflector A, which may be a prism as in Fig. 43, of the beam-combining rear optical unit in housing 106, which unit receives the beam through its front or first prism face 110, and transmits it by its second face 111. The prism B in the housing 118 has an etched line or cross hair 125 either centrally on its diagonal interior reflecting surface, or on its first or entering face as in Fig. 7^b, this hair line serving to ensure uniformity in the use of the optical system. The image of this reference line is the hair line 125 seen also in the diagrams Figs. 2 to 5.

The reference line 125 is preferably so applied as to be observed substantially at right angles to the halving line 134, and to appear, as seen in Figs. 2 etc., as substantially central of the field of observation; and the line 134 also is preferably about central, thus halving the field, due to the design of the housing 106 and the disposition of its windows, especially 109 and 111X, as seen in left elevation in Fig. 11. The reference or hair line 125 serves as an index or guide means, standing at right angles to the halving line. This element is important when one of the observed beams is received direct from the object; it may be placed in either beam and is carried by the gun, being preferably in the reflected beam and near the front or remote reflector, and therefore as far as practical from the eye.

The housing 118 may be positioned upon the barrel at a predetermined point lengthwise, according to the desired base line length, being shown closely to the rear of the front sight 115. Of course its first window must look unobstructedly upon the target and the housing must not obstruct the front sight as viewed from the rear sight. The housing and the fixed front sight may be combined in a single unit if desired, attachable as a whole.

For excessive ranges of shooting the described range-finding means may be supplemented by a telescopic means. Figures 7^a, 40, 41 and 42 illustrate a short type of telescope 127 available for the purpose, this being shown attached to the saddle 51 by an added bracket 126, and being arranged with its ocular 128 optically in line between the ocular of the rear or beam-combining unit and the eye. The telescope may be equipped with a cross hair located in its common focal plane rather than using a hair-line in the beam-collecting unit.

The principles of this invention are not limited to the particular optical and mechanical equipment shown by the drawings, since various kinds of mechanical and optical members, of different character and degree of precision or usefulness may be substituted or added according to the needs of the user. Such means as hoods, iris stops or field stops, or light-shielding tubes

surrounding the light path along or beyond the base line may be added without departure from the principles of the invention. As one example, an amici prism is sometimes to be preferred to the right angle prism of Fig. 43 for either the beam-collecting unit B or the beam-combining unit A, or any suitable roof-prism type of reflector may be used. As another variation, the prism A in housing 106 may occupy the bottom half or some other area instead of the upper half of the housing. Or, what has been termed the direct view TA of the target might reach the eye via some reflection or bending so long as the base line principle is not impaired, the two utilized light beams being divergent from the target by a measurable and effective, though small, angle. Or, a prism with only partly silvered reflecting face.

Reviewing the embodiment of the invention illustrated by the drawings, the first or front one of the light beams, namely TB, is received by the front isosceles right-angle deflecting prism B through its first window and prism face 123 and is deflected interiorly by the diagonal face to make its exit through the second face 124 of the same prism and through the housing rear window, passing thence to the preferably similar reflecting prism A in the rear housing 106, entering through the first window and prism face 110 whence it is deflected leftwardly to make its exit through the second prism face 111 and left window, and passing thence to the eye. The other light beam TA is received direct, or effectively so, from the target as through the right side window 108 in housing 106 and passes thence preferably without change out through the left window 109 to the observation point or eye E along with the deflected beam; thus affording a pair of comparable images which may be viewed one above the other to secure registry as in Fig. 2 or side by side to secure registry as in Fig. 3, or with full superposition as in Fig. 6, or by inversion vis-a-vis or symmetrically as in Fig. 5, according to the optical elements used and their arrangement, as will be further described.

The optical system as thus illustrated will produce an effect as in Figs. 2 to 4 with two erect images of the target, or with one image inverted as in Fig. 5. By an integration of the manual movements of the transversely held gun (Fig. 1) in relation to the target T, and the settings of the light-deflecting prism A in the rear housing 106 in relation to the rifle, the images viewed by the observer may be brought into registering alignment or otherwise into coincidence. The relative movements may appear somewhat complicated, as described, but inasmuch as the eye continuously observes the effect of every movement, the range-finding actions are made almost instinctively, so that practically the operation is essentially simple. For the sake of simplicity in the further description, it will be assumed that once the image pair is brought into the field of observation the rifle will be held stationary, and also that all movements of the indirect or deflected image are effected by the angular setting movements of the prism A contained in the housing 106 carried on the rotatable carriage 95, whose swing is effected by the manipulation of the thumb piece or knob 83 of the adjuster or duplex cam 78.

One mode of operation may be as follows. Assuming first that the firearm or rifle has been positioned so that a selected point of the direct

target image 129, Fig. 2, appears at one side, in this case the under side, of the line-of-separation or "halving line" 134 where it intersects with the reference line or cross hair 125, then a proper manipulation by the projecting pin or handle 107, Figs. 2^a and 31-35, will rotate slightly the housing 106 and its contained prism A about the housing longitudinal axis to bring the deflected image 130 into the field of view and at a slight distance above the halving line and above the direct image 129, as seen in Fig. 2^a.

By a further rotary adjustment of the housing 106 by its handle 107 the deflected image 130 may be shifted downward so that the selected point or apex, being any convenient object in the target, is brought very close to, but still beyond or slightly above, the halving line 134 which is usually the "trace" or lower edge of the bottom of the prism A; as seen in Fig. 2^b. This supplemental vertical shift of the deflected image toward the halving line is advantageous but is not essential so long as the two images are in comparable positions in the field of view, inasmuch as alignment of the two images along any part of the reference line 125 is all that is required for the range-finding operation, when such a line is provided.

To attain register, the deflected image 130 may now be shifted horizontally or in a direction parallel to the halving line until its selected point, shown as an apex, is on the reference line 125, as appears in Fig. 2^c. This adjustment is made easily as by the thumb and index finger turning the knurled head or knob 83 which operates through the controller or wedge cam 78 to actuate the lever 88 through the contact of its point 87 with cam part 86, and thereby the lever 91 through its contact with lever 88 at 90 and thereby by the pivoted carriage 95 through its contact with the lever 91 at the screw 94, and thereby to adjust and set the prism A in the housing 106 carried by the carriage 95. At the same time the sight bridge 61 is shifted automatically and correspondingly adjusted and set through the contact of the projection 76 with cam part 77; the vertical movement of the sight bridge carrying with it the plate or sight 63 and its peep-hole 65, to the correct shooting elevation for the found range. The sliding movement of the common adjuster or duplex wedge-cam 78 also carries its pointer 113 over the scale 112 to afford a reading of the range.

In the diagrams, Figs. 2 to 5, the substantially direct or rear image 129 of the target appears in the (lower) field 131 of direct view, meaning the view of the target seen along the beam TA; while the other image 130, seen along the beam TBA, appears in the (upper) field 132 of reflected view, the two views being separated by the halving line 134. In Figs. 6^a and 6^b when full coincidence of the image pair is attained, meaning register in both dimensions, this combined image 133, in Fig. 6^b, represents coalescence of the two images, wherein any lack of register is especially easily observable.

Fig. 3 represents the appearance of the field of view when the two target images have been aligned as to their salient or apex points along the reference line 125 while the firearm is held vertically with the barrel and base line upright. Fig. 4 shows the corresponding condition for some position of the firearm other than horizontal or vertical. In both of these cases the apexes have been put in register, that is, both falling upon the reference line 125.

Fig. 5 shows the field of view when the deflected upper image is inverted, as by a special or roof-edge prism or equivalent substituted for either erect prism shown, and brought into alignment or coincidence by a shift like that in Fig. 2^c.

Fig. 6^a shows how the complete coincidence of images in the field of view may be obtained; as by the use of a semi-transparent reflector which occupies the entire passage area of housing 106; the full area of the through window 108-109 being open for the direct view of the target through the transparent mirror or prism, whose reflecting surface may be thinly silvered. Then, as shown in Fig. 6^a, there exists the field 131 of direct view, with the deflected image field 132 superimposed thereon, while the deflected target image 130 is seen approaching full coincidence with the direct image 129. Fig. 6^b shows the full coincidence attained, of the two images at 133, which is the general equivalent in results to Figs. 2^c, 3, 4 and 5, but with the advantage of more exact visual observation of true register for range finding with the base type of finding means.

The curve of the range-finding contact face 26 of cam 78 is derived from the curve obtained when range distances are plotted as ordinates and the required angles of rotation of housing 106 and its prism A are plotted as abscissas. Likewise the curve of contact face 77 is derived from the curve obtained when distances are plotted against successive increments of elevation of the rear sight as required for successive ranges and selected trajectories. It will be evident, therefore, that these two curved cam faces, cooperating in unison, first, translate the curve representing increments or angles of rotation of the deflect prism A in housing 106 into a straight line and thereby produce the uniformly spaced scale 112, and second, simultaneously translate this straight line into the curve of the corresponding increments of elevation of the rear shooting peep-sight aperture 65.

These cam contours of the adjuster cam are preferably designed, as shown, of extended length so that they may avoid undue steepness of slant and be more easily manufactured to the degree of accuracy required of them, while minimizing wear. The curve of cam face 77 is such as to be responsive to the trajectory pertaining to the particular ammunition with which the gun is to be fired.

The minuteness of the quantitative values involved in range-finding triangulation emphasizes the value of the substantially long base-line AB which is available with the manner of use of this invention upon a shoulder firearm. Even with this ample base-line, of say 25 inches, the rotation of the reflecting prism A required for a shift from 100 to 200 yards is small, and may approximate 12 minutes of angle, and for a shift from 500 to 600 yards is much smaller, about 0.75 minute or 45 seconds of angle, which is substantially below the average resolving power, about 1 minute of angle, of the human eye; thereby usually presenting difficulty in distinguishing between and adjusting for target ranges of about 500 to 600 yards.

However the aligning power of the eye is far better than its resolving power, being of the order of 4 to 12 seconds of angle of the distant targets, which fact, with this invention, substantially overcomes the visual deficiency, in range-finding, by the bringing into register of the two images, reflected and direct, by the adjustment described. Since, between 500 and 600 yards the angular dif-

ferentiation is about 45 seconds, the eye power of alignment of 4 to 12 seconds is far more than ample, and would serve for ranges considerably beyond 600 yards.

5 While the quantities recited are well above the stated limits of the power of alignment possessed by the unaided normal eye the addition of a short telescope of prism type will greatly improve long-range accuracy; such an optical telescope being shown in Figs. 40, 41 and 42, and indicated in dash lines in Fig. 7^a.

It should be noted that if the actual target contains no salient or sharply defined pattern or area, as a vertical line or apex, which can present a pair of images adapted to be aligned across a horizontal line of separation, as the "halving line" 134 of Figs. 2 to 6, 11 and 35, the firearm may then be swung about into a vertical or inclined position, as represented respectively by 10 Figs. 3 and 4. When the actual target is devoid of any well defined point or line, some prominent feature of an adjacent object may serve as a substitute in obtaining the range of the actual target.

20 The following details are noteworthy: The base 25 range-finder on the firearm as described may be used by the shooter in the standing, sitting or prone postures with almost equal facility. The range-finder on the firearm may also be used conveniently as a periscope for reconnaissance, as 30 by pointing the gun upwardly and preferably blocking the direct view window 108. The knurled heads or adjusting knobs, 83 for range-finding and 67 for wind allowance, may be 35 equipped with click mechanisms to indicate audibly the changes made in gun elevation or windage adjustment, thereby to permit easy correction of aim from the observation of the point of impact of a previous shot. The knurled head or thumb-nut 83 may also be graduated around its rim or 40 elsewhere thereby to serve as a subdivider of the spaces on the scale 112 and afford finer adjustment. The range-finder means and the cooperating rear sight means are both of such compact shape and size as to be practically mountable 45 on the gun and to offer no obstacle to the usual operations of the firing bolt, to the loading by clip or singly, to the ejection of the empty cartridge, or to other conventional operations; while 50 the embodying of the invention on the gun sacrifices none of its regulation functions or facilities.

On the other hand, the range finding elements and features hereof possess certain novel utility apart from their use on a gun, namely, by mounting them on a supporting bar representing a barrel, making use of the disclosed elements numbered 78 to 114 and 118 to 134, or simplifications thereof, without using the other illustrated parts pertaining to the gun or its sighting means. In this aspect the range finder is of the fixed base type, with a rigid bar or support 117 of at least full length of the optical base line and on which the other elements are carried. These include the near reflector A, located at the near end of the base, whereat the observations are taken; and the remote reflector B at the far end thereof, the latter being fixedly mounted at a slant to act upon the first light beam TB received transversely from the distant object T by bending the beam through approximately a right angle and directing it longitudinally along the base line to the near reflector A. The near reflector has a supporting turret or carriage 95 upon which it is mounted for angular or rotational adjustment with the turret about an upright axis, whereby 65 the reflector A may be set to a variable slant to

act upon the received once-bent first beam and bend it again through approximately a right angle in a direction away from the object and toward the observer's eye E for viewing this indirect first image adjacently to a second or direct image thereof, such as the direct view of the target which is seen alongside of the twice reflected image. To determine the range, the described manual setting means may be used for causing rotation of the turret and thereby a fine angular adjustment of the near reflector whereby, under observation, such two images may be brought into mutual register or coincidence with differing distances of object, and along with these the scale and index, as before, to read the setting thus attained and thereby to determine the range of the object. The manual actuator or thumbpiece 83 operates the turret-rotating mechanism which includes the cam 77, 86 and a motion reducing train 87 to 94 actuated by the cam and connected to an extended part or arm of the turret to give the latter and the reflector the desired fine angular adjustment necessary for scientific determination of the distance of the object. It is further useful for range finding 10 5 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

ence guide or index means 125 to aid in setting the parts to achieve coincidence of images.

There have thus been described a shoulder firearm or gun with conventional sighting means, together with a range finding means, operable in a manner to embody the principles of the present invention; and since many matters of combination, construction, arrangement and detail may be variously modified without departing from such principles it is not intended to limit the invention to the disclosed features specifically disclosed except to the extent set forth in the appended claims.

What is claimed is:

1. A manually borne gun carrying rear and front shooting sights with a shiftable rear sight setting device operable to coordinate the gun elevation with the range of the target; and said gun carrying also a base-type coincidence range-finder means having first and second optical systems delivering images of the distant target at the observation point, and the first system having rear and front optical reflector elements located near the rear and front sights respectively thereby affording a base line between said reflectors arranged adjacently lengthwise of the gun-barrel, said range-finder having a shiftable setting contrivance operable under visual observation to set the finder to correspond with the target range; the front reflector being mounted at a slant to the base line to bend the first image beam to the rear reflector, at the position of which the observations are taken; and a common adjuster or controlling cam means operable to shift both said setting device and said setting contrivance in such coordination that the gun elevation in any setting of the sights corresponds with the range determined by the setting of the range-finder; together with a turret or carriage turnable on an upright axis, the rear reflector being mounted to turn with said turret thereby to impart angular adjustment to the rear reflector, with means for setting the turret to vary the reflector position and thereby the angle of second reflection of the first beam in a direction from the distant object, for observing adjacently the two images in bringing them into register; and there being an apertured carrier or walled housing which carries the rear reflector and is mounted upon the turnable turret to swing or tilt thereon about an axis substantially parallel to the base line and independently of the turning of the turret and rear reflector about such upright axis, whereby the carrier and reflector may be swung to bring the first image into a field of view adjacent to that of the second image in advance of turning the turret to shift the first image into coincidence with the second image.

2. A manually borne gun carrying rear and front shooting sights with a shiftable rear sight setting device operable to coordinate the gun elevation with the range of the target; and said gun carrying also a base-type coincidence range-finder means having first and second optical systems delivering images of the distant target at the observation point, and the first system having rear and front optical reflector elements located near the rear end and front sights respectively thereby affording a base line between said reflectors arranged adjacently lengthwise of the gun-barrel, said range-finder having a shiftable setting contrivance operable under visual observation to set the finder to correspond with the target range; the front reflector being mounted

Referring further to the reference or hair line 125, this serves as a guide or index for locating one of the two images with reference to the other, assisting in adjusting a selected or axial ray of either one of the light beams to a predetermined location, or the selected rays of both of the light beams. The index guide 125 is preferably on or near the remote reflector of a first light beam and affords uniformity, and the necessary accuracy, in bringing the two images into coincidence, when the second beam is a direct-viewed one. While shown as a straight or hair line it could be of various kinds, as an odd number of parallel lines, a number of small circles, concentric or aligned, or other forms, whether at a surface of a reflector, or interior or exterior thereto.

The range-finding means may be considered as having two optical systems for comparison, delivering their light beams and images adjacently at the observation point; at least one, the first, of said systems being indirect, having a remote first reflector and a near second reflector, along the base line, and set at angles for double reflection of beam as described; and the second optical means being either indirect or direct, but preferably direct, and so shown, for gunsight purposes; this arrangement calling for the use of the refer-

at a slant to the base line to bend the first image beam to the rear reflector, at the position of which the observations are taken; and a common adjuster or controlling cam means operable to shift both said setting device and said setting contrivance in such coordination that the gun elevation in any setting of the sights corresponds with the range determined by the setting of the range-finder; together with a settable carriage or rotatable turret swingable about an upright axis adapted to vary the angular position of the rear reflector and thereby the angle of one of the beams for bringing the beams into mutual register; and a separate settable means or reflector carrier shiftable independently of the first settable means and adapted to vary the position of the rear reflector to bring one of the beams into position within the field of view; the second optical system comprising a wall or structure providing apertures or passages giving an unobstructed direct view of the target in a viewing field adjacent to the field of the indirect view provided by the first optical system.

3. A manually borne gun carrying rear and front shooting sights with a shiftable rear sight setting device operable to coordinate the gun elevation with the range of the target; and said gun carrying also a base-type coincidence range-finder means having first and second optical systems delivering separate images of the distant target at the observation point, and the first system having rear and front reflectors located near the rear and front sights respectively thereby affording a base line between said reflectors arranged adjacently lengthwise of the gun-barrel, said range-finder having a shiftable setting contrivance operable under observation to set the finder to correspond with the target range; the front reflector being mounted at a slant to the base line to bend the first-image beam to the rear reflector, for re-reflection to the observation point; and a common adjuster means operable to shift both said setting device and said setting contrivance in such coordination that the gun elevation in any setting of the sights corresponds with the range determined by the setting of the rangefinder; together with a carriage or turret turnable on an upright axis and upon which turret the rear reflector is mounted, thereby to impart angular adjustment to the rear reflector by the operation of said setting contrivance and thereby to vary the angle of second reflection of the first beam in a direction from the distant object, for observing adjacently the two images in bringing them into register; said common adjuster comprising a manual actuator or thumb piece and a contoured cam actuated thereby, and said setting contrivance comprising a motion-reducing train actuated by the cam and connected to an off-center part or extended arm of the turret; and there being a carrier or walled housing mounted upon the turret and carrying the rear reflector and having openings or windows for the admission and egress of the two light beams; and the carrier housing having a swivel mounting on the turret to permit, independently of the turret setting operation, the manual swing or shift of the carrier and reflector about a longitudinal axis substantially parallel to the base line, thereby permitting preliminarily the bringing of the first or indirect image properly into the field of view before effecting the range-finding and sight-setting adjustments by the operation of the common adjuster.

4. A gun and range-finder combination as in

claim 3 and wherein the contoured cam is mounted slidably for its manual operation, and is of contour to translate its uniform scale of ranges into angular reflector adjustments corresponding to such ranges; and wherein said cam is adapted to adjust the turnable turret and reflector to shift the first image along the halving line toward and from the line of coincidence, while the independent swinging movement of the carrier housing on the turret acts to shift such image toward and from the halving line; and wherein is a visible cross-line or hair extending at right angles to the halving line so that the first and second images may be mutually aligned while one is yet somewhat removed from the halving line, such cross-hair being on or near the remote reflector.

5. A manually borne gun having front and rear shooting sights near the muzzle and breech ends respectively of the barrel and having a shiftable rear-sight setting device operable to set the gun elevation to the range of the target; and operatively combined therewith and mounted near the ends of such barrel a base-type coincidence range-finder means having the barrel for its base; said range-finder for a first light beam from the target having a front optical reflector mounted slantingly near the front sight, and a rear re-reflector mounted slantingly near the rear sight, the same being operative to direct such first beam to a common viewing point or eyepiece near the breech, the parts being constructed to provide for a second light beam a direct path from the target to such common eyepiece; said range-finder having a shiftable setting contrivance operable under visual observation to vary the slant of said re-reflector to bring the reflected first light beam into coincidence with the direct light beam at the viewing point; and a common adjuster operable manually to shift said setting device and said setting contrivance in such mutual coordination that the gun elevation in any setting of the sights corresponds with the range determined by the setting of the range-finder; the front reflector being mounted at a fixed slant to the base line to bend and direct the first beam to the rear reflector, at which observations are taken, and the rear reflector having a rotatable carriage or turret turning on an upright axis by which turret angular adjustment is imparted to said rear reflector to cause such first beam to be bent through a variable angle approximating a right angle in a direction away from the distant object for observing in adjacent fields of view the two images, and said setting contrivance being operative for adjusting the turret and carried reflector, whereby under observation the two images may be brought into mutual register; and there being associated with said turret an apertured housing or carrier carrying the rear reflector and mounted upon the turret to swing or tilt about an axis substantially parallel to the base line, and manual means preliminarily to swing the housing and reflector to bring the first image into a field of view adjacent to that of the second image; the housing swing operating to shift the first image toward and from the halving line between the fields, while the turret rotation operates to shift the first image along the halving line toward and from the reference hairline.

6. A manually borne gun having front and rear sights near the muzzle and breech ends respectively of the barrel, with a shiftable sight-setting device operable to adjust the rear sight and gun elevation to the range of the target; and coopera-

tive therewith and mounted near the ends of the barrel a monocular base-type range-finder operable upon the first of two light beams from the target and having a front reflector mounted slantingly near the front sight, and a rear reflector mounted slantingly near the rear sight, these being operative to transmit indirectly the first beam to a common viewing eyepiece near the breech; such range-finder being constructed to admit a second light beam on a direct path from the target to the eyepiece; and such range-finder having a shiftable setting contrivance operable under visual observation to vary the slant of said rear reflector to bring the twice reflected first light beam into coincidence with the direct second light beam at the viewing point; and a common operable adjuster manually to shift said setting device and said setting contrivance in such mutual coordination that the gun elevation in any setting of the sights corresponds with the range determined by the setting of the range-finder; the rear reflector being carried on a rotatable carriage or turret member turning on an upright axis and by the turning of which an angular adjustment is imparted to the rear reflector to cause such first beam to be bent through a variable angle into position for observing the two images in adjacent fields of view, whereby under observation the two images may be brought into mutual register; there being a reference means interposed in the first beam path well frontward of the rear reflector and providing a mark or up-

right hairline adapted to aid setting for coincidence; and there being an apertured housing or carrier member for the rear reflector, the same being mounted upon the rotatable turret to swing thereon about an axis substantially parallel to the base line, said carrier having manual means to swing it and the reflector to bring the first image into a field of view adjacent to that of the second image; the housing swing operating to shift the first image toward and from the halving line between the fields, while the turret rotation operates to shift the first image along the halving line toward and from the reference hairline.
